UNITED STATES PATENT OFFICE

AUGUSTUS C. DURDIN, JR., OF CHICAGO, ILLINOIS

PUMPING APPARATUS FOR SEWAGE AND OTHER LIQUIDS

Application filed April 27, 1927. Serial No. 187,007.

This invention relates to apparatus for pumping sewage and other liquids containing more or less solid substances. A centrifugal pump is usually employed in apparatus of this kind and one of the objects of the present invention is to provide improved means for preventing the more or less solid substances from entering the pump and clogging the same or causing serious injury thereto. Another object is to provide pumping apparatus of this kind wherein a plurality of centrifugal pumps may be connected to or interposed in the conduit for the sewage water or other liquids and having means whereby the pumps operate alternately or in a regular sequence, thereby reducing the wear and tear upon the pumps. Another object is to provide means in pumping apparatus of this kind in which the control means for the pumps operate to start more than one pump in case the incoming liquid exceeds the capacity of one pump. Another object is to provide a separating device or straining device for each pump interposed between the inlet to the apparatus and the pump and arranged in such manner that the incoming material is strained or screened before entering the pump and thereafter discharged from the apparatus when the pump is started, whereby the pump is not endangered or liable to become clogged.

With these and other objects and advantages in view, this invention consists in a pumping apparatus embodying a tank or other receptacle in which is contained one or more motor operated centrifugal pumps having its inlet opening communicating with the interior of the tank and a separator or strainer for each pump interposed in the inlet pipe of the tank and connected with the discharge end of each pump, whereby the more or less solid substances entering the tank, are separated or strained from the liquid before the liquid enters the pumps. The invention further consists in pumping apparatus embodying a tank or receptacle and a plurality of alternately acting pumps therein capable of acting simultaneously, and a separator or strainer interposed in the inlet conduit of the tank, and connected with the

discharge ends of the pumps. It further consists in the several novel features of construction, arrangement and combination of parts hereinafter fully set forth and claimed.

The invention is clearly illustrated in the drawings accompanying this specification, in which:

Fig. 1 is a view, partly in side elevation and partly in central vertical section, of pumping apparatus embodying a simple form of the present invention; Fig. 2 is a horizontal section taken on the line 2—2 of Fig. 1; Fig. 3 is an elevation of the apparatus looking in the direction of the arrow 3 in Fig. 1 and showing the tank partly broken out to illustrate parts that would otherwise be hidden from view; Fig. 4 is a detail view of a certain control device for effecting alternate and simultaneous action of the two pumps employed; Fig. 5 is a detail vertical cross section taken on the line 5—5 of Fig. 3; Fig. 6 is a detail horizontal section taken on the line 6—6 of Fig. 1, and Fig. 7 is a detail vertical cross section taken on the line 7—7 of Fig. 1.

Referring to said drawing, the reference character 10 designates a tank or other receptacle of suitable size having a cover 11 upon which the pump motor or motors 12 are mounted. Two centrifugal pumps 13, are illustrated and said pumps are contained in the tank or receptacle 10 and located adjacent the bottom thereof. Each pump is connected to an associated motor 12 by a pump shaft 14 contained in a pipe or other housing 15 which may also form the supporting connection for the pump. The inlet end of each pump is indicated at 16 and its discharge end at 17. While operating as a pump, the liquid enters the pump through the inlet end 16 and discharges through the discharge end 17, but when the pump is idle, liquid may flow through it from the discharge end 17 to the inlet end 16. At such times the pump merely acts as a conduit for the flow of liquid through it.

Extending through the wall of the tank or receptacle 10 is the inlet fitting 18, which connects with the sewage water pipe (not shown) or other conduit employed for con-

ducting the sewage water or other liquids to the pumping apparatus. When two pumps are employed in an outfit the inlet fitting is in the form of a Y, each of the branches 18^a of which communicates with the discharge end 17 of a pump through a conduit, which may comprise a pipe 19, a check valve 20 interposed between the inlet fitting 18 and pipe 19, a fitting 22, and a separator or strainer 21. The check valves 20 open in a direction toward the pumps, whereby the incoming material may flow through said conduits and through the pumps and thereby enter the tank through the inlet ends of the pumps, the more or less solid substances being separated or strained from the liquid during the passage thereof through the separators of strainers 21. In accordance with the form of the invention illustrated in the drawing each pipe 19 is connected to its associated separator or strainer 21, by a T fitting 22, and one branch of each T fitting 22 is connected to a discharge pipe 23, which leads out through the tank or receptacle 10 and is connected to the discharge pipe or conduit (not shown) of the system by a fitting 24.

While the construction of the separators or strainers 21 is immaterial to this invention broadly considered, the one shown serves well for the purpose of illustration. As shown, each separator or strainer comprises a cylindrical casing 21^a which forms a continuation of the discharge pipe 23 and is connected at the top with a T fitting 22 and at the bottom with the discharge end 17 of a pump and contains a screen or other separating device 21^b preferably of cylindrical form having a bottom 21^c and an open upper end secured to the casing 21^a. Obviously liquid passing down through the separator or strainer 21 may escape outwardly through the perforations in the screen 21^b and pass on through the discharge end of the pump and enter the tank through the inlet end of the pump, whereas more or less solid substances will be caught in the cylindrical screen and held therein until subsequently discharged through the open end thereof.

When a plurality of pumps are used, as for instance two pumps, it is preferable to have only one pump operate at a time so as to minimize the wear on the pumps and it is also desirous that the pumps operate alternately and that both operate in unison if the material accumulates in the tank faster than it can be discharged by one of the pumps. In other words if the capacity of one pump is not sufficient to discharge the accumulated matter as rapidly as it accumulates in the tank then both pumps are started to avoid any backing up of the accumulated material.

The means shown for controlling the operation of the two pumps, comprises two float

operated switch mechanisms 25, 25 one for each pump motor, each of which switch mechanism comprises an electric switch 26, a float rod 27 having spaced buttons 28, 29 thereon and arranged for engagement with the switch lever 30 and having in the tank and on the lower end of the float rod a ball float 31. The switch is supported by a standard or other support 32 mounted on the cover of the tank. Obviously as the liquid rises in the tank each float is carried upward and at a certain predetermined upper level the button 28 engages the switch lever 30 and closes the switch thereby starting the motor. In order to have the motors operate alternately, a control device 33 is provided upon each float rod, which device is constructed and arranged to make the associated float rod effective for the purpose of closing the switch only upon the alternate upstrokes of the float rod. One form of control device is more fully shown and described in an application for patent on means for operating electric switches and other mechanism, filed by me on December 29, 1926, Serial No. 157,856. Briefly each float rod comprises an upper section 27^a and a lower section 27^b, the lower one having the hollow, cylindrical member 33^a of the control device secured to it and the upper one having the member 33^b secured to it. The annular wall of the member 33^a may be formed with a continuous groove or track having long sections 33^c and short sections 33^d connected thereto by oblique sections, in which travels the other member 33^b, which usually comprises a pin on the upper rod section 27^a. The arrangement is such that when the lower section 27^b of the rod 27 of the float rod moves upward, during one of its strokes, a relatively short section of the groove or track is moved relative to the pin 33^b before the lower end of the groove or track engages the pin and lifts the upper section 27^a of the rod, thereby closing the switch, and starting the associated pump and discharging the liquid. As the liquid lowers, the float and float rod move down and the cylindrical member 33^a of the control device moves down relative to the pin 33^b (the upper float rod section being held stationary by the engagement of the button 29 with the switch lever 30). As the pin approaches the upper end of the short groove, it encounters an oblique portion and enters the top portion of the groove. When the float nears its lower limit it moves the entire float rod down thereby opening the switch and stopping the associated motor. During the next up stroke of the float rod the pin enters the relatively long part of the groove or track so that while the lower section of the float rod may be lifted to the same predetermined height as before, the upper section will not be moved far enough to close the switch. In this manner it will be observed

that each float rod closes the switch connected thereto during each alternate up stroke of the float and float rod. By properly setting the control devices 33, the switch to one pump is closed by the control apparatus each time that the liquid reaches a predetermined level in the tank and the pumps are thereby operated alternately. The arrangement is such however, that in case the liquid in the tank rises above the predetermined level, both floats and float rods will thereupon be lifted higher and consequently the inactive one will be lifted far enough to close the switch controlled thereby, thus causing both motors to be set in operation and both pumps to be operated, whereby the tank may be emptied as rapidly as it fills.

In cases of installation, where the tank is furnished by one concern and the pumps and other apparatus are furnished by another concern, it sometimes happens that the pipe connections between the inlet to the tank and the pumps do not line up perfectly and to compensate for any misalignment, I provide special joints between the pipes 19 and check valves 20, and between said pipes and the fittings 22. As shown in Fig. 6, apertured plates 34 are secured to the ends of each check valve 20 and fitting 22, which plates contain central openings a trifle larger in diameter than the diameter of the pipe 19, whereby the pipe may have a considerable amount of vertical and horizontal play with respect to the check valve and fitting. Collars 35 encircle the pipe 19 and are connected to the check valve and fitting 22 by bolts 36, and packing rings 37 are placed between the plates 34 and collars 35 and forced into contact with the pipe 19 by tightening up the bolts 36. The opposing faces of the plates 34 and collars 35 have beveled portions surrounding the central openings thereof, which engage with the packing rings whereby when the bolts are tightened up leak proof joints are obtained between the pipe 19 and check valve 20 and fitting 22, regardless of any misalignment between said parts. Furthermore by providing a joint of this character between the check valve 20 and fitting 22 the parts may be readily disconnected in the tank in case it becomes necessary to remove any part for the purpose of repair or replacement. In order to entirely shut off the inflow, I provide valves 38 between the inlet fitting 18 and check valves 20 which may be closed whenever necessary to make repairs. Conveniently, each valve 38 may comprise a flat narrow casing 38^a having a removable top 38^b and a flat plate 38^c within the casing and having an opening therethrough for the passage of liquid. The valve may be closed by removing the cover and raising the plate sufficiently to close the passage through the valve casing.

It is sometimes necessary to provide a sep-

arate inlet to the tank for liquids that are not conducted thereto through the inlet fitting 18 and in such cases a fitting 39 is provided at one side of the tank which fitting is connected to the inlet pipe for such liquids. When an additional inlet pipe is used it is preferable to provide a strainer 40 for the inlet of each pump 13.

In the operation of the apparatus above described and assuming that both pumps are stationary, liquid and other matter enters the tank through the inlet fitting 18, passes through the check valves 20, pipes 19, fittings 22 and strainers 21, and the liquid enters the pumps through their discharge ends and escapes into the tank through their inlet ends. As the liquid rises in the tank, both floats 31 are lifted and one of the control devices 33 being set so as to operate one switch lever 30, the float rod actuates the switch lever of one of the switches when its liquid reaches a certain predetermined level, thereby closing the circuit to one of the pump motors, whereby the pump associated therewith is started and the liquid within the tank is pumped back through the strainer or separator 21 associated with the pump in operation and the accumulated foreign matter is discharged with the liquid through the pipe 23 and on to the sewer or other receptacle into which the liquid is discharged. Inasmuch as one of the pumps has been stationary during the operation of the other pump, incoming liquid may enter the fitting 18 and pass through the strainer or separator associated with the stationary pump and the strained liquid emptied into the tank. If, however, the incoming liquid enters more rapidly than one pump may eject it, the other pump will be started as soon as the level of the liquid in the tank reaches a place where the float rod is lifted high enough to close the switch in the stationary pump motor. When the tank has been emptied to a certain predetermined low level and the floats lowered sufficiently to open the switches, the motors are stopped and remain stationary until the tank subsequently fills to the predetermined high level, whereupon the pump which was previously inactive or put into operation as an emergency, is now put into operation and the tank again emptied. In this manner the pumps operate alternately in discharging the contents of the tank and simultaneously in case of necessity.

With a screen 21^b of cylindrical form and surrounded on its sides by the casing 21^a, the solid matter collects in the screen while the liquid passes to and through the idle pump into the tank 10. When the pump is started, the liquid is discharged back through the casing 21^a and inwards through the apertures of the screen, and around the collected solid matter therein, there compressing the solid

matter and bodily discharging the mass from the screen.

The apparatus above described is very simple in construction, may be built economically and is highly efficient in operation. Because of the peculiar arrangement of the separators or screening devices, they are self-cleaning and prevent the more or less solid substances from entering the pumps and clogging them or causing possible injury thereto.

More or less variation of the exact details of construction is possible without departing from the spirit of this invention; I desire, therefore, not to limit myself to the exact form of the construction shown and described, but intend, in the following claims, to point out all of the invention disclosed herein.

I claim as new, and desire to secure by Letters Patent:

1. Pumping apparatus comprising in combination a liquid receiving receptacle, an inlet conduit entering said receptacle and adapted to be connected with a source of liquid supply, a centrifugal pump contained in said receptacle and having an inlet side and a discharge side within said receptacle, the inlet side opening directly into said receptacle, an upright discharge pipe leading away from the discharge side of the pump and connected to said inlet conduit, and a screen within said pipe and located between the discharge side of the pump and the connection between the inlet conduit and discharge pipe.

2. Pumping apparatus comprising in combination a liquid receiving receptacle, an inlet conduit entering said receptacle and adapted to be connected with a source of liquid supply, an inwardly opening check valve in said inlet conduit, a motor driven centrifugal pump contained in said receptacle and having an inlet side and a discharge side within said receptacle, the inlet side opening directly into the receptacle, an upright discharge pipe leading from the discharge side of the pump and connected to said inlet conduit, and a cylindrical screen open at the top and contained within the discharge pipe, said screen being located between the discharge side of the pump and the connection between the inlet conduit and discharge pipe.

3. Pumping apparatus comprising in combination a liquid receiving receptacle, an inlet conduit entering said receptacle and adapted to be connected with a source of liquid supply, an intermittently acting motor driven centrifugal pump contained in said receptacle and having an inlet side and a discharge side within the receptacle, the inlet side opening directly into the receptacle, an upright discharge pipe leading from the discharge side of the pump and connected

to the inlet conduit, and a screen within said discharge pipe and located between the discharge side of the pump and the connection between the inlet conduit and the discharge pipe.

4. Pumping apparatus comprising in combination a liquid receiving receptacle, an inlet conduit entering said receptacle and adapted to be connected with a source of liquid supply, a pump having its inlet side opening into said receptacle, a discharge pipe leading away from the discharge side of said pump and connected to said inlet conduit, and a cylindrical screen within said discharge pipe for receiving solid matter, said screen being of less diameter than the discharge pipe to afford an annular water passage around the same and located between the discharge side of the pump and the connection between the inlet conduit and discharge pipe.

5. Pumping apparatus comprising in combination a liquid receiving receptacle, an inlet conduit adapted to be connected with a source of liquid supply, a pump having an inlet side connected to said receptacle, a discharge pipe leading away from the discharge side of the pump and connected to said inlet conduit, and a cylindrical screen within said discharge pipe for receiving solid matter, said screen being of less diameter than the discharge pipe and located between the discharge side of the pump and the connection between the inlet conduit and discharge pipe, there being an annular discharge liquid passage between said screen and discharge pipe and surrounding the screen, said annular passage being closed at one end.

6. Pumping apparatus comprising in combination a liquid receiving receptacle, an inlet conduit therefor and adapted to be connected to a source of liquid supply, a pump having its inlet side in communication with said receptacle, a discharge pipe leading away from the discharge side of the pump and connected to said inlet conduit, and a cylindrical screen within said discharge pipe for receiving solid matter therein, there being an annular liquid passageway closed at one end and surrounding said screen.

7. Pumping apparatus comprising in combination a liquid receiving receptacle, an inlet conduit entering said receptacle and adapted to be connected with a source of liquid supply, a centrifugal pump contained in said receptacle and having an inlet side and a discharge side within said receptacle, the inlet side opening directly into said receptacle, a discharge pipe leading away from the discharge side of the pump and connected to said inlet conduit, and a cylindrical screen within said discharge pipe of less diameter than the discharge pipe and located between the discharge side of the

pump and the connection between the inlet conduit and discharge pipe, there being an annular liquid passageway in said discharge pipe surrounding said screen.

8. Pumping apparatus comprising in combination a liquid receiving receptacle, an inlet conduit entering said receptacle and adapted to be connected with a source of liquid supply, a centrifugal pump having an inlet side communicating with the interior of said receptacle, a discharge pipe leading away from the discharge side of the pump and connected to said inlet conduit, and a cylindrical screen within said discharge pipe of less diameter than the discharge pipe and located between the discharge side of the pump and the connection between the inlet conduit and discharge pipe, there being an annular liquid passageway in said discharge pipe surrounding said screen.
